EYE PROTECTIVE DEVICE

Original Filed Jan. 27, 1934

UNITED STATES PATENT OFFICE

2,066,838

EYE PROTECTIVE DEVICE

Donald E. Kimball, Cleveland, Ohio, assignor to
The Safety Equipment Company, Cleveland,
Ohio, a corporation of Ohio

Application January 27, 1934, Serial No. 708,647
Renewed June 4, 1936

12 Claims. (Cl. 2—14)

This invention relates to eye protective devices; and it is among the objects of the invention to provide a device having goggle cups formed to effectively cover the eyes and capable of being quickly adapted to any size head and being easily put on or off. Other objects and advantages will appear as the description proceeds.

To the accomplishment of the foregoing and related ends, the invention then, comprises the features hereinafter fully described and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1 is a perspective view of an embodiment of the invention; Fig. 2 is a side elevational view, parts being omitted; Figs. 3 and 4 are detail elevations; Fig. 5 is a reduced-scale plan detail; Fig. 6 is a fragmentary sectional view of a modification; and Figs. 7 and 8 are elevational details of the same.

Referring more particularly to the drawing, there is shown a protective goggle comprising goggle cups 2, a nose-bridge 3 and holding means 4. The goggle cups are formed of suitably light material, and while in some cases metallic shells may be used, generally synthetic resin molded shells are preferable. Each goggle cup is equipped with a glass 5 at its front, the glass being held by any suitable means, as for instance a screw cap 6, and at the rear the cup has its edges recessed above and below to accurately fit the super- and sub-orbital portions of the face. Means for ventilation is desirably provided, as for instance screens 1 which may be set in the outer quadrant. If desired, perforations may be additionally provided in the cup body above and below. At the outer rear edge of each cup, the holding means 4 comes into engagement. As shown more in detail in Fig. 2, this means involves a chain 8 of suitable form, preferably as dumb-bells or small balls or beads held serially together and allowing some internal take-up movement from bead to bead, such movement however, being limited both as to extension and compression, the chain being freely flexible and being engageable at its ends to the cups in a take-up fastener means engageable with any selected link of the chain. The fastener means as shown in the form illustrated comprises a projecting lug 9 slotted to receive the chain at its narrow part

be bent down sufficiently tightly to prevent disengagement of the chain from out of the notch. Such lug may be rigid on the cup or preferably may have hinge-like connection onto a bail 9a of the outer rear end of the cup. As seen, such fixture allows of the chain being inserted at any selected position, that is at any link desired, and in a device of size-range required the surplus links for any adjustment need not be many in any case, and are unnoticeable. Associated with the chain 8 is a take-up spring 12, providing sufficient resiliency to yield and allow easy removal, or when the device is in place serving to hold it sufficient tautly to prevent accidental displacement. In the form shown, the spring comprises a coil section 15 extending through a partial arc of the band 4, and being fastened at its ends to the chain 8 by having the ends of the spring wire sufficiently tightly clamped down between beads. By locking the spring in place when the chain 8 is held in a compressed position, that is with the links brought together in closest positions, the spring 12 as finally locked to the chain will readily allow of stretching up to the limit of the extended length of the corresponding chain portion, and as indicated, this is sufficient for easy placement. The spring 12 may extend through a longer or shorter length as desired in any given case.

Surrounding the chain 8 and the spring 12 is a tubular cover 13 of flexible material, for instance textile fabric, braid, etc. Advisably, the cover will be removable with respect to the chain, so as to facilitate renewals, etc., and preferably a snap-on connection may be employed, the ends of the cover being provided with a metallic ring 14 somewhat flattened and having sufficient resiliency to snap over the ears 10, 11, on the goggle cup. The same resiliency allows the ring 14 to be sprung loose when desired, by applying sufficient pressure.

While the nose bridge 3 between the goggle cups may be of varied construction, including take-up coil spring means 3a, Fig. 1, or other features, in some instances it may include a section of take-up chain 8a, Fig. 6, like the main holding chain described. Such chain may engage regulably in each goggle cup, so as to allow of lengthening or shortening as desired. For instance, the end of the chain may extend through a key-hole-like slot in the goggle cup, the enlarged portion 15 of the slot being of size to just allow passage of the chain, while the narrow or slotted portion 16 of the key-hole is of a size to just receive the narrow portions of the links or the wires between beads. By setting the chain to the length de-

- sired between the goggle cups, and pushing the narrowed portion back into the slot 16, and then putting the cap 6 on in place, the edge of the latter covers the enlargement 15 of the key-hole slot 5 and finally prevents any disengagement of the chain from its adjusted position. A guard 17 of tubular form, for instance a tube of rubber, celluloid or other desired material, may be applied over the chain as a further refinement.
- 10 Since eye protective devices generally have to be worn for hours at a time, and under uncomfortable conditions of exposure to heat, flying particles, etc., it is of particular importance that a device be accurately fitting and comfortable to the wearer. The present invention makes possible a realization of highly effective placement over the eyes, and yet without discomfort even on long continued wearing. In the event also that the device is to be used by others, quick adjustment to the precise head size may be quickly had.
- 15 Other modes of applying the principle of the invention may be employed, change being made as regards the details described, providing the means stated in any of the following claims, or the equivalent of such, be employed.
- 20 I therefore particularly point out and distinctly claim as my invention:—
1. An eye protective device, comprising goggle cups and holding-means for holding the same in place, including a chain, a tubular cover therefor, and snap-securing means for anchoring the cover.
  2. An eye protective device, comprising goggle cups and holding-means for holding the same in place, including a chain, a tubular cover therefor, and a resilient snap for anchoring the cover-end.
  3. An eye protective device, comprising goggle cups, holding-means for holding the same in place, including a chain, slotted lugs on each goggle cup for engaging narrowed link portions of the chain, bent-down ears for locking the chain in place, a coil spring surrounding said chain for at least part of its length, a tubular cover for said chain and spring, and snap-securing means for anchoring the cover.
  4. An eye protective device, comprising goggle cups and holding-means for holding the same in place, including a chain, a slotted lug at the outer rear end of each cup for receiving a narrowed portion of the chain, ears for locking the chain against displacement from the slot, a tubular cover for the chain, and a resilient ring on each end of the tubular cover for snapping over said ears.
  5. An eye protective device, comprising goggle cups and holding-means for holding the same in place, including a bridge-chain between the cups, a head-band chain connecting the rear external end of each cup, a coil spring surrounding said chain for at least part of its length, take-up fastener means for adjusting the bridge-chain, take-up fastener means for adjusting the head-band chain, a tubular cover for said head-band chain and spring, and snap-securing means for anchoring the cover.
  6. A protective device comprising goggle cups and holding means including a connecting nose-bridge between the cups, a head-band chain con-

necting the rear outer ends of the cups and having take-up fastening for connecting at a selected link for length-adjustment, and a coil spring surrounding and tensioning a portion of the length of said chain.

7. A protective device comprising goggle cups and holding means including a connecting nose-bridge between the cups, a head-band chain connecting the rear outer ends of the cups and having take-up fastening for connecting at a selected link for length-adjustment, and a resilient tensioning means operating on a portion of said chain, whereby to adjust to general size and allow easy removal and placement without disturbing the size adjustment.

8. A protective device for application to the head of a wearer, with a chain head-band section conformable about the back of the head and having its ends connected to the protective device, a coil spring surrounding a part of the chain head-band section normally under tension rendering the head band extensible, and connecting means on the protective device for selectively engaging one of the end links of the chain, whereby the initial length of the band may be varied independently of the spring.

9. A protective device for application to the head of a wearer, comprising a head-band portion of chain-like character, a stretchable normally un-extended portion in association therewith, being conformable about the back of the head, and connecting means on the protective device engageable with optional links of the portion of chain-like character, whereby the initial length may be varied independently of the stretchable portion.

10. A protective device for application to the head of a wearer, comprising a stretchable normally un-extended head-band portion and a non-stretchable link-presenting portion, in length conformable to a major arc of the head, and means for connecting the non-stretchable portion to the protective device at selected links, whereby to adjust to general size and allow easy removal and placement without disturbing the size adjustment.

11. A protective device for application to the head of a wearer, comprising a stretchable normally un-extended head-band portion, a cover therefor, and a non-stretchable length-adjusting portion, in length conformable to a major arc of the head, and means for connecting the non-stretchable portion to the protective device at varied points on said non-stretchable portion, whereby to adjust to general size and allow easy removal and placement without disturbing the size adjustment.

12. A protective device for application to the head of a wearer, comprising a stretchable normally un-extended head-band portion, and a non-stretchable length-adjusting portion, in length conformable to a major arc of the head, and means for connecting the non-stretchable portion to the protective device at varied points on said non-stretchable portion, whereby to adjust to general size and allow easy removal and placement without disturbing the size adjustment.

DONALD E. KIMBALL.
